UNITED STATES PATENT OFFICE

NORMAN H. SAUNDERS, OF HOMEWOOD, ILLINOIS, ASSIGNOR TO RESERVE HOLDING COMPANY, OF KANSAS CITY, MISSOURI, A CORPORATION OF DELAWARE

TELEPHONE SWITCHING SYSTEM

Application filed July 30, 1927, Serial No. 209,569. Renewed October 30, 1929.

This invention relates to telephone systems in general, but more particularly to toll switching systems in which all toll connections within a certain area are established and 5 supervised from a main toll board.

In telephone systems extending over an area including several more or less widely scattered communities or exchanges, interconnected by toll or long distance lines, the 10 practice of completing and supervising all connections between the exchanges of the different communities, as well as all the connections to and from outside points, from a main toll board located in one of the exchanges is 15 often advantageously followed. In a telephone system of this kind, each exchange may not be connected directly with every other exchange in the system, but may be connected only with one or two of the nearest exchanges. 20 For this reason special consideration must be given to the methods employed in carrying out the above practice in order that it may be done in the most economical manner, both in regard to the amount of equipment needed 25 and in regard to the number of trunks used to set up a connection.

Switching systems for use in a situation of this kind, whereby the toll operator may be called from any one of the exchanges in the 30 system over one of the trunks extending to the exchange in which the toll board is located and whereby the toll operator may then control the establishment of the desired connection over the most direct route and maintain 35 supervision thereof over that same trunk line, have previously been developed. Certain of these prior systems such as shown in the Lomax application Ser. No. 174,734, filed March 12, 1927, and in the Madsen Patent No. 1,556, 40 793 granted Oct. 13, 1925, however, are open to the criticism that when a calling subscriber sets up a connection to the toll operator over a trunk, although the toll operator can control the setting up of a connection to the desired 45 called subscriber over that same trunk she must do so without permitting the calling subscriber to replace his receiver. In other words, she cannot verify the name and number given by the calling subscriber. Other 50 systems such as disclosed in the application of

Arthur J. Ray and Harley McElyea, Serial No. 446,319, filed Feb. 19, 1921, though not open to the above objection involve the use of rather complicated control circuits.

The main object of this invention consists 55 in the provision of an improved and simplified switching arrangement for use in a telephone system as described above, not having the above objections.

A particular feature of this new and improved switching arrangement is that the toll operator after being called over a trunk line may either establish the desired connection over that same trunk line without requiring the calling subscriber to replace his receiver, 60 or may ask the calling subscriber to replace his receiver and release the existing connection to the toll operator and then reestablish the connection to the calling subscriber over that same trunk line to verify the name and 65 number given and then set up the connection to the called subscriber.

Another particular feature of the invention is that in the latter procedure described above, in which the toll operator first re-establishes the connection to the calling subscriber and then extends the connection to the called subscriber, the switch control circuit associated with one of a pair of switches operated under its control to set up a connection to the calling subscriber is automatically shifted into association with the other switch of the pair to control the setting up of a connection to the called subscriber responsive to the calling 75 subscriber's answering.

The object of the invention and the various features thereof, those mentioned and others not specifically stated as such, will be described in detail in the following specification with the aid of the accompanying drawings. 80 The drawings illustrate by means of the usual schematic circuit diagrams and trunking diagrams a section of a telephone system involving the principles of this invention. It is understood of course, that the invention is in no 85 way limited to any particular system, the one shown in part in the drawings having been chosen merely for illustration.

The drawings, to be more easily understood, should be placed with Fig. 2 directly 90

below Fig. 1 with the corresponding lines in alignment. The apparatus shown in the two drawings with the exception of that shown in the dotted section in the lower left hand corner of Fig. 2, is located in one exchange, which will be referred to as exchange A. The exchange A is an automatic exchange serving the subscribers of one community, and all calls within this community are established automatically without the aid of an operator. The automatic switches for setting up these local connections have been shown diagrammatically. For example, the line from the local subscriber's substation A¹ terminates in the individual line-switch LS, which has access together with other lineswitches to the local selectors, such as selector S. In the banks of the local selectors access is had to one or more groups of connectors, each group being accessible in a particular level. Each group of connectors has access to a separate group of subscribers' lines. The connector C shown, is one of the group having access to the group of subscribers' lines including the line to substation A².

Exchange A is connected with the exchanges of two other communities by two groups of trunk lines. The trunk line comprising conductors 101 and 102 is one of the group from the exchange of one community which will be referred to as exchange B, and the trunk line comprising conductors 201 and 202 is one of the group from the exchange of another community which will be referred to as exchange C. Each of these trunk lines terminates at exchange A in an individual lineswitch such as the lineswitch LS¹ or LS².

Exchange A is also connected with the exchange of another community, which will be referred to as exchange T, by one or more toll trunk lines such as the one comprising conductors 311 and 312. At this latter exchange, the main toll board is located, from which all toll connections for the system are completed. At the exchange A, this trunk line is divided into two branches. The outgoing branch, that is, the branch over which connections to the toll board are extended, comprises conductors 103, 104, and 105, and together with the corresponding branches of the other toll trunk lines to the exchange T, is accessible in the banks of rotary line switches such as LS¹ and LS² and also in a particular level in the banks of the local selectors. The incoming branch, that is, the branch over which the toll operator controls the setting up of toll connections, comprises conductors 103' and 105' and terminates in a dual call repeater DCR. The corresponding branches of the other toll trunks from the exchange T likewise terminate in similar dual call repeaters.

At the dual call repeater DCR, the incoming branch is further divided into two branches, one branch comprising conductors

111, 112, and 113 which terminates in the selector S¹, the other branch comprising conductors 115, 116, and 117 which terminates in the selector S².

Those levels of banks of the local selectors in which access is had to the various groups of connectors of exchange A are multiplied with the corresponding levels of the selectors associated with dual call repeaters, so that the local selectors and the selectors associated with the dual call repeaters have common access to the connectors for completing connections local to the exchange A. The trunks extending to exchanges B and C are also accessible in separate levels in the banks of the selectors associated with the dual call repeaters. The local selectors, however, do not have access to the trunks to exchange B and to exchange C.

The line switches LS¹ and LS² in the exchange A may be of any suitable type, such as the well known rotary type having no normal position. The selectors, both the local selectors and the selectors associated with the dual call repeaters, and also the connectors may be of any suitable type, such as the well known Strowger vertical and rotary type. The dual call repeater DCR forms a particular part of this invention and will be described in detail subsequently.

At the exchange T, the trunk lines from the exchange A terminate at the main toll board in jacks, the trunk line comprising conductors 311 and 312 terminating in the jack J. Individual to each trunk is a call lamp such as lamp L¹, a disconnect lamp such as lamp L², a dialling key such as key K for associating the dial D with the trunk, and two relays for controlling the supervisory circuits.

Exchanges B and C are also assumed to be automatic exchanges, with suitable switches for completing local connections and connections to the trunk lines extending to the exchange A. These trunk lines may terminate at their respective exchanges in incoming selectors, and may be accessible to local selectors by way of repeaters in the well known manner.

With the objects of the invention and the layout of the system and the apparatus shown in mind, a further understanding and appreciation of the invention and its features may be gained from the detailed description of the operations thereof. To describe the operations, it will first be assumed that a subscriber served by the exchange B wishes to be connected with the subscriber at substation A² at the exchange A. This connection can be obtained only by the aid of the toll operator at exchange T. The calling subscriber at exchange B therefore removes his receiver and dials the toll or long distance number, which causes automatic switches in the exchange B to extend a connection over

one of the trunk lines extending to exchange A, such as, for example, the one comprising conductors 101 and 102. The extension of the connection to the exchange A over this trunk line causes the lineswitch LS¹ to operate in the usual manner and select the outgoing branch of an idle trunkline extending to the exchange T. It may be assumed that the branch selected by the lineswitch LS' is the one comprising conductors 103, 104, and 105 of the trunk comprising conductors 311 and 312 terminating at the toll board at the exchange T in jack J.

As a result of the establishment of this connection, a circuit is closed for line relay 2 of the dual call repeater DCR which circuit includes the two trunk conductors 103 and 105 and extends by way of contacts 22 and 25 to the upper and lower windings of relay 2. Line relay 2 operates and closes a circuit for release relay 3. Release relay 3 operates and grounds the release conductor 104 to mark this trunk busy to the other line switches having access thereto at contacts 14, and grounds the holding conductor 124 at contacts 16. The placing of ground on the holding conductor 124 closes a circuit for the upper winding of supervisory control relay 53 over the circuit including contacts 60 and 69. Relay 53 operates over its upper winding and closes a holding circuit for itself at contacts 67 independent of contacts 60 and 69, and connects battery potential through a protective resistance to the automatic exchange end of the simplex control circuit which includes line relay 51, trunk conductors 311 and 312 in parallel, and supervisory relay 302 at the toll board. This circuit normally has ground potential connected to the automatic exchange end thereof at contacts 12, at contacts 37, and also via the resistance R, and to the toll board end thereof at contacts 307. The connection of battery potential to the automatic exchange end of this circuit produces a current flow thereover and causes the energization of line relay 51 at the exchange A and also relay 302 at the toll board. Relay 51 in energizing closes a circuit for relay 52. Relay 52 operates and opens the initial energizing circuit for the upper winding of relay 53 by separating contacts 60, prepares a circuit for relay 55 at contacts 63, and grounds the release conductor 116 at contacts 62.

At the toll board, the operation of relay 302 closes the circuit of the answering lamp L¹ at contacts 308. The lighting of the lamp L¹ indicates to the toll operator that a connection is desired. The toll operator answers the call by inserting the plug of one of her cords (not shown) into the jack J. This operation closes the circuit of relay 301 by closing contacts 321. Relay 301 in operating, substitutes battery potential through a re-

sistance for the normal ground connection at the toll board end of the control circuit by separating contacts 307 and closing contacts 306, and also opens the circuit of lamp L¹ and prepares the circuit of lamp L² by separating contacts 303 and closing contacts 304. Since battery potential is now connected to both ends of the control circuit, both relay 302 at the toll board and line relay 51 at the exchange A release. Relay 51, in releasing, closes a circuit for relay 55 which includes contacts 63 of relay 52 (relay 52 being slow acting maintains its armature attracted for an interval after its circuit is opened). Relay 55 operates and closes the circuit of relay 54 at contacts 73. Relay 54 operates and at contacts 71 closes a circuit for relays 7 and 56 in series, this circuit including contacts 68 and also contacts 33. Relay 7 operates and locks itself to the holding conductor 124 at contacts 34, closes the circuit for the polarizing winding of relay 6 at contacts 31 and by separating contacts 33 opens its initial energizing circuit and by closing contacts 32 closes a circuit for the lower winding of relay 53, the latter circuit likewise including contacts 68 and 71. Relay 53 is differentially wound and therefore the energization of its lower winding causes this relay to release. Relay 53, in releasing, opens the locking circuit for its upper winding at contacts 67 and opens the circuit of its lower winding at contacts 68, and by separating contacts 66 and closing contacts 65 disconnects battery potential from the exchange end of the control circuit and again substitutes the normal ground connections thereto. Since battery potential is now connected to the toll board end of the control circuit and ground potential is connected to the exchange end thereof, relay 302 and line relay 51 again energize. Relay 51, in energizing, again closes the circuit of relay 52. Since the operations described responsive to the release of 51, namely the operations of relays 55, 54, 7, and 56, and the deenergization of relay 53 take place in a comparatively short time, relay 52 does not restore during this interval, and relay 302 at the toll board and relay 51 at the exchange A are deactuated only for an interval.

Relay 56 which is energized in series with relay 7 during the momentary deenergization of the line relay 51, performs the following circuit changes: By the closure of contacts 75 and 78 a bridge is placed across the conductors 115 and 117 (after relay 53 is deactuated and relay 51 is reoperated) which causes the energization of the line and the release relays (not shown) in the selector S² associated with the dual call repeater DCR, thereby preparing this selector for operation. At contacts 80 a circuit is prepared for short circuiting the lower winding of relay 6 during dialling as will be described presently. At contacts 81 a condenser bridge is

also placed across the conductors 115 and 117.

After inserting the plug into the jack J and throwing her listening key (not shown), the toll operator may converse with the calling subscriber, the calling subscriber giving his name and number and also the name or number of the subscriber with whom he wishes to speak. It will be assumed that the toll operator, by recognizing the voice or otherwise, feels that it is unnecessary to verify the name given as the calling subscriber and elects to complete the connection while the present connection with the calling subscriber is maintained, thus giving that much faster service. The toll operator, therefore, then actuates the dialling key K, and then dials the number of the called subscriber. Actuating the dialling key K inserts the dial D in the impulsing circuit and also short-circuits the supervisory relay 302. Relay 302 therefore deenergizes, causing the extinguishment of the lamp L². The dialling of the digits of the called number causes corresponding interruptions in the current flow over the control circuit by intermittently disconnecting the battery potential from the toll board end which causes the impulsing relay 51 at the exchange A to deenergize and reenergize correspondingly. At each deenergization of relay 51, the circuit is closed for relay 55 at contacts 59. Relay 55 operates and again causes the operation of relay 54 by closing its circuit at contacts 73, and being slow acting remains operated during the dialling of each digit, but deactuates after the impulses of each digit. Relay 55 when operated also short-circuits the lower winding of the supervisory relay 6 by closing its contacts 72, and relay 54, in energizing, opens the condenser bridge across the conductors 115 and 117 by separating contacts 70. The momentary deenergizations of line relay 51 corresponding to the digits dialled causes corresponding interruptions in the bridge across the conductors 115 and 117 at contacts 57.

In response to the dialling of the first digit of the called number, selector S² operates and raises its wipers opposite the corresponding level in which access is had to the group of connectors having access to the line to substation A² (this being the second level as shown in the drawings), and then rotates them in search of an idle connector. Responsive to the dialling of the next two digits, the connector C, assuming that this is the one selected, operates to position its wipers in engagement with the bank contacts at which the line of substation A² terminates. The connector C then automatically signals the called subscriber by the intermittent application of ringing current to the called line.

After completing the dialing of the number of the subscriber at substation A², the

toll operator restores the key K to normal which again disconnects the dial from the impulsing circuit and removes the short-circuit from relay 302. Relay 302 therefore again operates and causes the lighting of the lamp L².

When the subscriber at substation A² answers, the signalling is interrupted and the talking circuit is completed and the current over the conductors 115 and 117 is reversed by the operation of the back bridge relay in the connector C in the usual manner. As a result, the current in the lower winding of polarized supervisory relay 6 is reversed which causes this relay to operate. By the separation of contacts 29 the direct ground connection to the exchange end of the control circuit by way of contacts 37 is removed. Ground potential is now connected to the exchange end of the impulsing circuit only through resistance R, since both the line relay 2 and the supervisory relay 6 are energized. The current flow over the control circuit is now reduced to the extent that relay 302 deenergizes, thus causes the extinguishment of the lamp L² which notifies the toll operator that the called subscriber has answered. The current flow through the resistance R, however, is sufficient to maintain relay 51 operated.

The two subscribers may now hold conversation, the talking circuit extending from the exchange B over conductors 103 and 105, through the repeating coil R of the dual call repeater DCR, conductors 115 and 117, through the selector S² and the connector C to the called substation A². The toll operator also has supervision of the conversation over the trunk line comprising conductors 311 and 312.

As soon as either the calling or the called subscriber replaces his receiver at the termination of the call, the toll operator is informed thereof by the lighting of the lamp L². The replacement of the receiver at the calling station at the exchange B causes the release of the automatic switches at exchange B and opens the circuit of the line relay 2 at the exchange A. Relay 2, on deenergizing, again connects direct ground potential to the exchange end of the control circuit by closing contacts 12. The replacement of the receiver at the called substation A² causes the connector C to again reverse the current flow over the conductors 115 and 117 in the well known manner and thereby cause the deenergization of relay 6. Relay 6, in deenergizing, again connects direct ground potential by way of contacts 37 to the exchange end of the control circuit by closing contacts 29. The replacement of direct ground potential as a result of either operation causes the current flow over the control circuit to increase to the normal value, which causes relay 302 at the toll board to ener-

size and again cause the lighting of the lamp L^2 . Thus the toll operator is notified as soon as either one of the subscribers replaces his receiver, even though the other subscriber still has not replaced his receiver.

5 The deenergization of relay 2 caused by the replacement of the receiver at the calling substation also opens the circuit of the release relay 3 by separating contacts 11. Relay 3, on deenergizing, disconnects one ground connection from the holding conductor 124 by separating contacts 16, and by permitting contacts 15 to close, a circuit is closed for relay 5, ground being maintained on the holding conductor 124 by relay 52. By the separation of contacts 14, ground potential is removed from the release conductor 104 which permits the lineswitch LS^1 to restore to normal. Relay 5 energizes and again places ground potential on conductor 104 at contacts 21 thereby marking the trunk used busy to the lineswitches such as LS^1 and LS^2 . Incidentally, by closing contacts 20 and 26 and contacts 23 and 24 a bridge 25 is closed across the conductors 111 and 113 which causes the line and the release relay (not shown) of the selector S^1 associated with the dual call repeater DCR to operate, but this operation has no function at this 30 particular time.

On perceiving a lighted condition of the lamp L^2 , indicating that the conversation has terminated, the toll operator removes the plug of her cord from the jack J. This operation opens the circuit of relay 301 by separating contacts 321. Relay 301 deenergizes and by separating contacts 306 and closing contacts 307 again disconnects battery potential from the toll board end of the control circuit and again connects ground potential thereto. Since ground potential is now connected to both ends of the control circuit, both relay 302 at the toll board and relay 51 at the exchange A deenergize. Relay 51, in 40 deenergizing, opens the bridge across the line conductors 115 and 117 by separating contacts 57 and also opens the circuit of relay 52 by separating contacts 58. The opening of the bridge across conductors 115 and 117 45 opens the circuit of the line and the release relay of the connector C and allows the connector C to release, but this does not cause the release of the selector S^2 , since ground is still maintained on the release conductor 50 55 116 by relay 52 at contacts 62. Relay 52 deenergizes a short time after its circuit is opened and by separating contacts 61 disconnects ground from the holding conductor 124 and thus opens the circuit of relay 5 and also 60 65 70 the circuit of relays 7 and 56, whereupon these relays deenergize and restore to normal. Incidentally relay 55 and relay 54 energize momentarily, the circuit of relay 55 being closed momentarily after relay 51 has released and 65 70 75 before relay 52 is released, but this operation

has no utility at this time. The separation of contacts 62 also removes ground from release conductor 116, permitting the selector S^2 to restore to normal. All the apparatus is now in its normal condition.

According to a special feature of this invention, should the calling subscriber wish further service after having finished speaking with the called subscriber, he may keep his receiver to his ear after the called subscriber has replaced his receiver, and when the toll operator removes the plug from the jack J upon receiving the disconnect signal, she will again be signalled by the relighting of lamp L^2 . To describe this feature let us assume, in a connection as previously described from exchange B via the dual call repeater DCR, to the substation A² that the calling subscriber in exchange B maintains his receiver to his ear, wishing further service after the called subscriber at substation A², has replaced his and after the toll operator had removed the plug of her cord from the jack J responsive to the lighting of the disconnect lamp L^2 responsive to the called subscriber's replacing his receiver. The removal of the plug from the jack J again initiates the deenergization of relays 51 and 52, and relay 55 is again operated momentarily when its circuit is closed by the closure of contacts 59 before relay 52 releases its armature and separates contacts 63. Relay 55 operates and causes the operation of relay 54. As soon as relay 55 and relay 54 restore, a circuit is again closed for the upper winding of differential relay 53, the same as when the call was first initiated, ground being present on the holding conductor 124 since relays 2 and 3 are still operated. Relay 53, in operating, again connects battery potential to the exchange end of the control circuit so that relay 302 at the toll board is again energized. Since relay 301 is now deenergized, lamp L^2 is again lighted. This indicates to the toll operator that the calling subscriber has not replaced his receiver and desires further service. The toll operator then reinserts the plug of her cord into the jack J, and after ascertaining the further wants of the calling subscriber may then complete any other connection including such as described by way of selector S^2 .

In the previously described connection, it was assumed that the toll operator felt no need in verifying the name and number of the calling subscriber, and thus completed the connection to the called subscriber while the calling subscriber maintains his receiver to his ear. In other cases however, she may need to verify the name and number of the calling subscriber, or she may need to look up some information before she can complete the desired connection. In such cases, according to a particular feature of this invention, she may ask a calling subscriber who

has called her in the manner described above to replace his receiver, and when she is ready, she will recall him and then complete the connection between him and the called subscriber.

To describe this method of completing a connection between a calling and a called subscriber, it will be assumed that a subscriber in the exchange B after calling the toll operator and informing her of the name of the called subscriber, replaces his receiver upon the toll operator's requesting him to do so, being informed that she will recall him presently. The toll operator also removes the plug of her cord from the jack J, again restoring all of the apparatus to normal.

When the toll operator is ready to complete the desired connection, she reinserts the plug of her cord into the jack J, operates the dialling key K, and then dials the number of the calling subscriber to reestablish a connection with him, and when he answers, she dials the number of the called subscriber, the connection between the calling and the called subscriber being completed as soon as the called subscriber removes his receiver. When the operator inserts the plug of her cord into the jack J, springs 321 are closed causing the operation of relay 301. Relay 301 in operating substitutes battery potential for the normally connected ground potential at the toll board end of the control circuit, which, since ground potential is connected to the exchange end of the control circuit, causes the operation of both relay 302 at the toll board and the impulsing relay 51 at the exchange A. Relay 302 at the toll board operates and closes the circuit of lamp L², causing this lamp to light. Relay 51 at the exchange A in operating closes a circuit of relay 52. Relay 52 operates and opens a point in the initial energizing circuit of the upper winding of relay 53 by separating contacts 60 and grounds the holding conductor 124 by closing contacts 61. The latter operation closes the circuit for relay 5, this circuit includes contacts 15, relay 3 now being deenergized. Relay 5 operates and grounds the release conductors 104 and 112 at contacts 21, at the same time closing the circuit for the polarizing winding of relay 4. By the closure of contacts 20 and 26 and contacts 23 and 24 a bridge is placed across conductors 111 and 112 extending to the selector S' associated with the dual call repeater DCR. This bridge includes the lower winding of relay 4, contacts 77, contacts 57, contacts 64, and contacts 74. The placing of this bridge across the conductors 111 and 113 causes the operation of the line and the release relay in the selector S', preparing this selector for operation.

After operating the dial key K, which again short-circuits relay 302 and extinguishes the lamp L², the toll operator dials the

number of the calling subscriber, causing line relay 51 to deenergize and reenergize, and open and close the bridge across the conductors 111 and 113 at contacts 57 correspondingly. Relay 55 and relay 54 operate during the dialing of each digit, now short circuiting the lower winding of relay 4 at contacts 72. Responsive to the dialling of the first digit, selector S' operates and raises its wipers opposite the level of bank contacts having access to the trunks extending to exchange B (which in the drawing is shown as the fourth level), and then automatically rotates them in search of an idle trunk in this level. It may be assumed that the trunk selected is the same trunk over which the calling subscriber called the toll operator, namely, the one comprising conductors 101 and 102. Responsive to the dialling of the remaining digits of the number of the calling subscriber, switches in exchange B operate to extend the connection to the calling subscriber's line, the last switch operated being a connector which automatically signals the calling subscriber in the usual manner.

When the calling subscriber answers, the signalling is interrupted and the current flow over the conductors 101 and 102 now connected to conductors 111 and 113 is reversed in the ordinary manner, thus reversing the current flow in the lower winding of relay 4. Relay 4 thereupon operates and by separating contacts 19 disconnects one ground connection from the exchange end of the end of the control circuit, and by closing contacts 18 closes an energizing circuit for relays 7 and 56 in series. Relays 7 and 56 operate and perform circuit changes as previously described, though the closure of contacts 32 of relay 7 has no utility in this instance, relay 53 not being operated. By the operation of relay 56, contacts 57 are now included in the bridge across conductors 115 and 117. Thus the control has now been automatically shifted to selector S', this having taken place responsive to the answering of the subscriber with whom connection was obtained via selector S'. Relay 56, in operating, also prevents the interruption of the bridge across conductors 111 and 113 by closing contacts 76 to hold the connection to the calling subscriber, the spring arrangement being such that these contacts close before contacts 74 and 79 are opened.

The operator now continues to dial, now dialling the number of the called subscriber, the calling subscriber being instructed to wait on the line. The selector S' operates responsive to the first digit of the called number to extend the connection to an idle connector having access to the called line, and the connector completes the connection responsive to the last two digits. When the called subscriber answers, relay 6 operates as previ-

ously described and by removing the remaining direct ground connection from the exchange end of the control circuit by separating contacts 29, causes the extinguishment of lamp L^2 (the operator having restored the dialling key K after completing dialling).
5

The two subscribers may now converse with each other, the talking connection extending from exchange B over conductors 101 and 102, through selector S' , over conductors 111 and 113, through the repeating coil R, over conductors 115 and 117, through selector S^2 to the called line. The toll operator may also hear the conversation over the trunk conductors 311 and 312 and the branch conductors 103' and 105'.

As in the previous case a toll operator is signalled as soon as either one of the subscribers replaces his receiver at the termination 20 of the call by the lighting of the lamp L^2 , the direct ground potential being replaced on the exchange end of the control circuit by the closure of contacts 29, by the release of relay 6 when the called subscriber replaces his receiver, or at contacts 19 by the release of relay 25 4 when the calling subscriber replaces his receiver. In this type of connection the same as in the previous type, on perceiving the lighted condition of the lamp L^2 , the operator releases the connection by removing the plug of her cord from the jack J, which opens the circuit of relay 51 and relay 302. Relay 51, in deenergizing, opens the circuit of relay 30 52 which likewise deenergizes and opens a circuit of relay 5 and also the holding circuit of relays 7 and 56. These three relays then restore to normal. The restoration of relay 56 opens the bridge across the conductors 115 and 117, allowing the release of the selector 35 S^2 and the connector used in the connection. The restoration of relay 5 opens the bridge across the conductors 111 and 113 thus allowing the release of the selector S^1 .

In this type of connection, the same as in 40 the previously described connection, should the toll operator remove the plug of her cord from the jack J while the calling subscriber still has the receiver to his ear, wishing further attention, the selector S^1 will not be released and the toll operator will again be signalled by the lighting of the lamp L^1 to notify her that the calling subscriber is still on the line. To describe these operations in a connection as just described, let us assume 45 that the calling subscriber maintains his receiver to his ear after the called subscriber has replaced his receiver (which caused the lighting of the lamp L^2) and after the toll operator removed the plug from the jack J. Since relay 4 is still operated in this case, the removal of the plug from the jack J, causing the release of relay 51 and relay 52, does not cause the deenergization of relays 5, 7, and 56, for the reason that ground is still maintained on the holding conductor 124 by way

of contacts 12, 18 and 34. These relays therefore remain energized. Since ground potential is present on conductor 124, relay 53 operates after relay 52 and relays 55 and 54 (the latter two relays being operated momentarily before relay 52 releases) restore over the circuit including contacts 60 and 69. Relay 53 again functions to connect battery potential to the exchange end of the control circuit which again causes the energization of relay 51 and at exchange A, and relay 302 at the toll board. Lamp L^1 again lights, indicating to the toll operator that the calling subscriber is still on the line. The toll operator may again insert the plug of the cord into the jack J which causes a momentary deenergization of relay 51, the momentary operation of relays 55 and 54, and the deenergization of relay 53 by the energization of its lower differential winding, all as previously described. The toll operator can now set up any other connection desired by the calling subscriber by way of selector S^2 .
70 75 80 85

The foregoing descriptions describe how connections may be completed from the exchange B to a subscriber in exchange A. From these it is obvious how connections can be completed from any one of the exchanges, A, B, or C, to any other of these exchanges, under the control of the toll operator at exchange T. It is also evident how connections can be completed to any of the exchanges A, B, or C from distant points beyond the exchange T, or to distant points from any one of these exchanges when the trunk line comprising conductors 311 and 312 is used for completing the connection. In the former case, only the selector S' is used in the extension of the connection, in the latter case, the toll operator may complete the connection 90 95 100 while the calling subscriber maintains the connection he established with the toll operator, if the toll operator thinks it unnecessary to verify the call, in which case neither selector S^1 or S^2 are used, or the toll operator may 105 request the calling party to replace his receiver and recall him by way of selector S' , in which case selector S^2 is likewise not used.

In order to prevent a transmission loss through the repeating coil R, and also to make it possible to give the toll operator the regular disconnect supervision in any connection in which selector S^2 is not used, special means have been provided for disconnecting the selector S^2 and also for disconnecting the normal ground connection at contacts 37 from the exchange end of the control circuit so that the disconnection of direct ground potential from the exchange end which controls the disconnect signal at the toll board 110 115 120 will be under the sole control of the one party in the exchange A, B, or C, to whom or for whom the connection was established.
125

To describe this feature, let us assume that a subscriber in exchange B has extended a

connection the toll operator via the trunk branch comprising conductors 103 and 105 and the trunk comprising conductors 311 and 312, and that the toll operator intends to complete the connection to some outside point while the connection to the toll operator is maintained. Some time before the final connection is completed, the toll operator operates the key K (the plug of her cord being in the jack J) and dials a special digit, which in this case is assumed to be the digit "1". This causes the selector S² to operate as previously described and raise its wipers opposite the first level of bank contacts and then 10 rotate them into engagement with the first set of contacts in this level across which relay 45 is bridged. Relay 45 thereupon operates and causes the operation of relay 46. Relay 46 in operating closes a circuit of relay 8. 15 Relay 8 operates and locks itself to the holding conductor 124 at contacts 36, disconnects selector S² from conductors 115 and 117 by separating contacts 35 and 38, and disconnects direct ground potential from the exchange end from the control circuit at contacts 37. The disconnection of the selector S² by the separation of contacts 35 and 38 permits the line and the release relay of this selector to release, but the selector is maintained operated by reason of ground being 20 maintained on the release conductor 116 at contacts 62 of relay 52. It is evident now that lamp L² will not light until the subscriber at exchange B replaces his receiver and thereby 25 causes the release of relay 2, which replaces direct ground potential on the exchange end of the control circuit at contacts 12.

If the toll operator chooses to recall the calling subscriber who wishes a connection to an outside point, the toll operator likewise 30 dials this special number to operate relay 8, but not until after the calling subscriber has answered after being recalled via selector S'. (In this connection it should be remembered that the toll operator, after calling a subscriber over selector S' is automatically put in control of selector S² responsive to that subscriber's answering.) In this case, after relay 8 has been operated by operating selector S², 35 in accordance with the digit 1, lamp L² will not be lighted until the calling subscriber at exchange B replaces his receiver and causes the release of relay 4 which replaces direct ground potential on the exchange end of the control circuit by closing contacts 19.

The same procedure is followed in the establishment of a connection from a distant point to a subscriber in any one of the exchanges A, B, or C.

It should also be noted that since the toll operator has control of the release of the selector S² it is possible for her to force the release of an existing connection should she find it necessary to do so by merely removing the plug of her cord from the jack J.

This completes the description of the various operations of the apparatus involved in this invention. What is considered new and is desired to have protected by Letters Patent is pointed out in the appended claims. 70

What is claimed is:

1. In a telephone system, a trunk, a first and a second switch, a line, means controlled over said trunk for operating said first switch to extend a connection to said line, and means responsive to the answering of the call by the party on the line for causing circuit changes so that further operations of said first means operates said second switch. 75

2. In a telephone system, a trunk, a first and a second switch, a line, switch controlling means common to said switches, means for associating said switch controlling means with said first switch, means for operating said switch controlling means to cause said first switch to extend a connection to said line, and means responsive to the answering of the call by the party on the line for associating said switch controlling means with said second switch. 80

3. In a telephone system, a trunk, a first and a second switch associated with said trunk, means for extending a connection to either end of said trunk, switch controlling means, means responsive to the extension of a connection to one end of said trunk for associating said switch controlling means with said first switch, and means responsive to the extension of a connection to the other end of said trunk for associating said switch controlling means with said second switch. 90

4. In a telephone system, a trunk, a first and a second switch associated with said trunk, means for extending a connection to either end of said trunk, switch controlling means, means responsive to the extension of a connection to one end of said trunk for associating said switch controlling means with said first switch, means responsive to the extension of a connection to the other end of said trunk for associating said switch controlling means with said second switch, 105 means for operating said switch controlling means to control the operation of the switch with which it is associated, means operative after the first switch is operated for associating said controlling means with said second switch so that said switch controlling means thereafter controls the operation of said second switch, and means controlled by said switch controlling means for maintaining either or both of the switches operated after they have been operated. 110

5. In a telephone system, a trunk having 125 two branches, a switch for each branch, a line relay for controlling the operation of said switches successively over the respective branches, and means controlled by said line relay for maintaining one of said switches 130

operated after it has been operated while controlling the operation of the other switch.

6. In a telephone system, a trunk having two branches, a switch for each branch, means for placing a bridge including a set of impulsive contacts across the conductors of one branch to control the operation of the switch associated with said one branch, and means operable after the switch associated with said one branch is operated for placing a bridge including said set of impulsive contacts across the conductors of the other branch to control the operation of the switch associated with this said other branch.

15 7. In a telephone system, a trunk having two branches, a switch for each branch, means for placing a bridge including a set of impulsive contacts across the conductors of one branch to control the operation of the switch associated with said one branch, means operable after the switch associated with said one branch is operated for placing a bridge including said set of impulsive contacts across the conductors of the other branch to control the operation of the switch associated with said other branch, and means for placing another bridge across the conductors of said one branch while said set of impulsive contacts are included in the bridge across the conductors of said other branch to maintain the switch associated with said one branch operated.

25 8. In a telephone system, a trunk having three branches at one end, a line relay responsive to impulses sent over said trunk line, means operative when a certain condition exists on the first branch for causing said line relay to repeat impulses over the second branch, and means operative when a certain other condition exists on the first branch for causing said line relay to repeat impulses over the third branch.

35 9. In a telephone system, a trunk line having three branches at one end and terminating at a manual switchboard at the other, a calling and a called line, means controlled by the party on the calling line for establishing a connection to the manual switchboard via one of said branches and said trunk line, and means including a relay common to the other two of said branches controlled by the operator at said manual switchboard over said trunk line for establishing a connection between said calling and said called line via the other two branches of said trunk line in series and exclusive of said one branch.

45 10. In a telephone system, an exchange, a manual switchboard, an interconnecting trunk having three branches at said exchange, a calling and a called line, means for extending a connection from said calling line to said manual switch board over said trunk via the first of said branches, means controlled by the operator over said trunk line for either completing the connection to said

50 called line via the second of said branches while the connection from the calling line to the manual switchboard is maintained, or for reestablishing a connection from the manual switchboard to said calling line via the third of said branches, after the first connection from the calling line to the manual switchboard has been released, and then completing the connection to said called line via the second of said branches.

55 11. In a telephone system, an exchange, a manual switchboard, an interconnecting trunk having three branches at said exchange, a calling and a called line, means for extending a connection from said calling line to said manual switch board over said trunk via the first of said branches, means controlled by the operator over said trunk line for either completing the connection to said called line via the second of said branches while the connection from the calling line to the manual switchboard is maintained, or for reestablishing a connection from the manual switchboard to said calling line via the third of said branches, after the first connection from the calling line to the manual switchboard has been released, and then completing the connection to said called line via the second of said branches, a signal at said switchboard, and means for operating said signal in either 60 type of connection when the party on either line replaces his receiver.

65 12. In a telephone system, an exchange, a manual switchboard, an interconnecting trunk having three branches at said exchange, a calling and a called line, means for extending a connection from said calling line to said manual switch board over said trunk via the first of said branches, means controlled by the operator over said trunk line for either completing the connection to said called line via the second of said branches while the connection from the calling line to the manual switchboard is maintained, or for reestablishing a connection from the manual switchboard to said calling line via the third of said branches, after the first connection from the calling line to the manual switchboard has been released, and then completing the connection to said called line via the second of said branches, operator controlled means for releasing the connection, a signal at said switchboard, and means for operating said signal should the operator release the connection before the calling subscriber in either 70 type of connection has replaced his receiver.

75 13. In a telephone system, a first exchange, a second exchange, a trunk connecting said exchanges, a calling and a called line, means at said first exchange controlled over said trunk line from said second exchange for extending a connection to said calling line and for then extending a connection to said called line to establish a talking connection between 80 85 90 95 100 105 110 115 120 125

- said calling and said called line, a signal at said second exchange, and means controlled by the party on either line when he replaces his receiver for operating said signal.
14. In a telephone system, a first exchange, a second exchange, a trunk connecting said exchanges, a calling and a called line, means at said first exchange controlled over said trunk line from said second exchange for extending a connection to said calling line and for then extending a connection to said called line to establish a talking connection between said calling and said called line, a signal at said second exchange, and means controlled by the party on the called line when he removes his receiver and by the party on either line when he replaces his receiver for operating said signal. 70
15. In a telephone system, two exchanges, a trunk comprising two conductors connecting said exchanges, branches of said trunk at one exchange, each branch comprising two conductors, an automatic switch for each branch for extending connections to subscriber's lines, and means controlled from the other exchange over the two conductors of said trunk in parallel for controlling the operation of each switch over the two conductors of its associated branch in series to establish a talking connection between a subscriber accessible via one of said switches and a subscriber accessible via another of said switches. 75
16. In a telephone system, two exchanges, a trunk comprising two conductors connecting said exchanges, branches of said trunk at one exchange, each branch comprising two conductors, an automatic switch for each branch for extending connections to subscriber's lines, means controlled from the other exchange over the two conductors of said trunk in parallel for controlling the operation of each switch over the two conductors of its associated branch in series to establish a talking connection between a subscriber accessible via one of said switches and a subscriber accessible via another of said switches, a signal at said other exchange, and means controlled over the two conductors of one of the branches in series and over the two conductors of said trunk in parallel for operating said signal. 80
17. In a telephone system, a trunk line comprising two conductors, a calling line having access to said trunk line, a called line, and means controlled over said two conductors in parallel for extending a connection to said calling line and for then extending a connection to said called line to establish a talking connection between said calling and said called line. 85
18. In a telephone system, a trunk line comprising two conductors, a calling and a called line, means controlled over said two conductors in parallel for extending a connection to said calling line and for then extending a connection to said called line to establish a talking connection between said calling and said called line. 90
19. In a telephone system, two exchanges, a trunk comprising two conductors connecting said exchanges, branches of said trunk at one exchange, automatic switches for extending said branches separately into connection with subscribers' lines, a manual switchboard at the other exchange, means for signalling the operator at said switchboard over said trunk line, and operator controlled means controlled over said two conductors in parallel for controlling the operation of said switches to establish a three way talking circuit including the operator and two subscribers accessible to said switches. 95
20. In a telephone system, a trunk line comprising two conductors and having two branches each comprising two conductors, and a line relay controlled over the two conductors of said trunk line in parallel for repeating impulses over the two conductors of each branch separately. 100
21. In a telephone system, a trunk line comprising two conductors and having two branches each comprising two conductors, a line relay controlled over the two conductors of said trunk line in parallel for repeating impulses over the two conductors of each branch separately, and means for determining over which branch said line relay is to repeat impulses. 105
22. In a telephone system, a trunk line having two branches, a line relay responsive to impulses sent over said trunk line, automatic switches, a calling and a called line, means for causing said line relay to repeat impulses over one branch to certain of said switches to extend a connection to said calling line, means responsive to the subscriber's answering for causing said line relay to repeat impulses over said other branch to operate other of said switches to extend the connection to said called line. 110
23. In a telephone system, a trunk line extending from an exchange to a manual switchboard and having substantially the same potential applied to both ends of a conductor of said trunk line, a calling line at said exchange and means for connecting it with said trunk line, means responsive to the establishment of said connection for applying a different potential to said conductor at the exchange to signal the operator at said manual switchboard, a called line, an automatic switch associated with said trunk line at the exchange, means responsive to the operator's answering the call for reapplying the normal potential to said conductor at the exchange, and means controlled by the operator for intermittently applying a differ- 115
- 120
- 125
- 130

- ent potential to said conductor at the manual switchboard to control the operation of said switch to connect with said called line.
24. In a telephone system, a trunk line extending from an exchange to a manual switchboard, a calling line at said exchange and means for connecting it with said trunk line, means responsive to the establishment of said connection for causing a current flow over a conductor of said trunk line in one direction to signal the operator at said manual switchboard, a called line, an automatic switch associated with said trunk line, an automatic switch associated with said trunk line at the exchange, means responsive to the operator's answering the call for reversing said current flow over said conductor, and means controlled by the operator for intermittently interrupting the reversed current flow to cause said switch to operate and connect with said called line. 70
25. In a telephone system, a trunk line extending from an exchange to a manual switchboard, a calling line at said exchange and means for connecting it with said trunk line, means responsive to the establishment of said connection for causing a current flow over a conductor of said trunk line in one direction to signal the operator at said manual switchboard, a called line, an automatic switch associated with said trunk line at the exchange, means responsive to the operator's answering the call for reversing said current flow over said conductor, means controlled by the operator for intermittently interrupting the reversed current flow to cause said switch to operate and connect with said called line, and means responsive to the party on the called line answering the call for changing the value of the reversed current flow to notify the operator that the call is answered. 75
26. In a telephone system, a trunk line having two branches, a switch associated with each branch, means responsive to digits sent over said trunk line for operating said switches separately and means responsive to a particular digit for disassociating one of the switches from its normally associated branch. 80
27. In a telephone system, lines, a trunk having two branches, a switch associated with each branch, means for operating one of said switches to extend a connection to one of said lines and for operating the other of said switches to extend a connection to another of said lines, and means responsive to the operation of the other of said switches to a particular extent for disassociating said other of said switches from its normally associated branch. 85
28. In a telephone system, a trunk line comprising two conductors, a calling and a called line, automatic switches, means controlled over said two conductors in parallel for extending a connection to said calling line via certain of said automatic switches and means controlled by the calling subscriber for rendering said first means effective for then extending a connection to said called line via certain other of said automatic switches to establish a talking connection between said calling and said called line. 90
29. In a telephone system, a trunk line terminating in two automatic switches and also accessible to subscribers, means for operating said switches separately, the switch operated depending on whether or not a subscriber has connected with said trunk line. 95
30. In a telephone system, a trunk line having three branches at one end, calling and called lines, means for extending a call from the calling line via one of said branches and the trunk line, and means controlled over the trunk line for establishing a connection between the calling and called lines via either the first and second branches in series or the second and third branches in series. 100
31. In a telephone system, a two conductor trunk line, branches of the trunk line each including two conductors, automatic switches terminating said branches, calling and called lines, and means controlled over the two conductors of the trunk line in parallel and the two conductors of the associated branches in series for directly operating the respective automatic switches to establish a connection between the calling and called lines. 105
32. In a telephone system, a trunk line comprising two conductors, a plurality of branches of said trunk line each comprising two conductors, and a line relay controlled over the two conductors of the trunk line in parallel for repeating impulses successively over the two conductors of each branch in series. 110
33. In a telephone system, a trunk line comprising two conductors, branches of the trunk line each comprising two conductors, and a line relay controlled over the two conductors of the trunk line in parallel for initially repeating impulses over the two conductors of one branch in series and for subsequently repeating impulses over the two conductors of the other branch in series. 115
34. In a telephone system, a trunk line, a plurality of branches of the trunk line, and a relay controlled over the trunk line for separately repeating impulses over said branches in pre-determined succession. 120
35. In a telephone system, a trunk line having a plurality of branches, a line relay controlled over said trunk line, and impulsive contacts on said relay included successively in said branches in predetermined order. 125
36. In a telephone system, a branched trunk line, a relay responsive to a plurality of series of impulses transmitted over the trunk line, means for causing said relay to repeat the first series of impulses over one branch of the trunk line to extend a connection to a called line, and means responsive to the com- 130

pletion of said connection for causing said relay to repeat the subsequent series of impulses over another branch of the trunk line to extend a connection to another called line.

37. In a telephone system, a branched trunk line, a line relay responsive to a plurality of series of impulses transmitted over the trunk line, each series of impulses corresponding to the digits of a called telephone number, means
10 for causing said relay to retransmit the first series of impulses over one branch of the trunk, and means effective incidental to the retransmission of the first series of impulses for causing said relay to retransmit a suc-
15 ceeding series of impulses over another branch of the trunk.

In witness whereof, I hereunto subscribe my name this 27th day of July, A. D. 1927.

NORMAN H. SAUNDERS.
